UNITED STATES PATENT OFFICE.

GEORGE H. SNOW, OF WALPOLE, MASSACHUSETTS.

GARMENT-SUPPORTER.

957,117.

Specification of Letters Patent.

Patented May 3, 1910.

Application filed July 24, 1908. Serial No. 445,127.

To all whom it may concern:

Be it known that I, GEORGE H. SNOW, a citizen of the United States, and a resident of Walpole, in the county of Norfolk and 5 Commonwealth of Massachusetts, have invented an Improvement in Garment-Supporters, of which the following description, in connection with the accompanying drawings, is a specification, like characters on 10 the drawings representing like parts.

My invention has reference to garment supporters, and refers particularly to supporters known as suspenders, used by men to support the trousers.

15 My invention comprises the novel features set forth in the following specification.

In the embodiment of my invention illustrated herein,—Figure 1 is a perspective view, parts being broken away; Fig. 2 is a 20 detail view upon an enlarged scale of one side of the belt attaching member; Fig. 3 is a similar view of the opposite side of the same; Fig. 4 is a cross section on the line $x-x$, Fig. 3; and Fig. 5 is a cross sectional 25 detail on the dotted line 5—5 of Fig. 2.

My invention comprises suspension members to be worn over the shoulders and a belt member carried thereby and adapted to be secured to the trousers or other garment 30 to be supported.

Referring first to Fig. 1, the suspension members comprise two shoulder straps 1—1, similar to the ordinary suspender straps and connected at a point below the upper portions 35 thereof and back of the shoulders of the wearer, by a back strap 2, which, in turn, is provided with a take-up buckle 3, and a connecting member 3^a adapted to engage an elongated ring 4, of the ordinary 40 type.

The shoulder straps 1—1 are provided respectively near their front lower ends, with suitable take-up buckles 5, which permit adjustment of the straps to the convenience 45 of the wearer and are also provided with suitable rings 5^b to receive the connecting members 5^c. The front connecting members 5^c may be conveniently disengaged from the ends of the shoulder straps 1 when desired 50 or necessary. The front connecting members 5^c and the rear lower ends of said shoulder straps are secured, respectively, in suitable manner to the out turned ends 5^a of V-shaped supporting members or 55 connectors 6.

The connectors 6 are made preferably of

wire, sufficiently rigid to keep the two ends of the straps 1 separated and to prevent them from being drawn together and pinching the shoulders by the weight of the 60 trousers thereon. Said members 6 may be provided with a woven or knitted covering a of any suitable kind to prevent the moisture from the body causing the same to rust, or it may be nickel plated or otherwise 65 treated for the purpose. The lower ends of the connectors 6 may be provided with ferrules over the woven covering, where it is embraced by the clasp 8.

The connectors 6 are engaged by suitable 70 detachable clasps 8, to which are connected straps 7, the lower ends of which are secured to the contracted ends of the inverted V-shaped, preferably wire hangers 9 secured to and preferably below or under the lower 75 edge of the garment supporting member, shown as a belt or band 10. This belt is constructed of any suitable material which is pliable laterally, to enable it to conform to the body of the wearer but which is sufficiently 80 rigid vertically to support the trousers, in proper position about the body the belt itself being suspended from the shoulders at two points only, preferably at the sides, by the straps 7. I have found that a 85 belt constructed of a fabric composed of a fine wire cloth, overlaid with a coating of gelatin or similar substance and covered upon the outside with cloth or any similar substance as desired, gives excellent results. 90 The inner surface of the belt may be left uncovered for washing and cleansing, to remove the effect of perspiration. The belt is provided with a take-up buckle 13 and a loop or ring 14 at one end, and a clasp 15 at 95 the opposite end, so that it may be adjusted to the waist measurement of the wearer and easily clasped or unclasped to apply the same to or remove it from position. These hangers 9 may be bent under and closely 100 against the belt and in addition thereto may be fastened in place by stitching, or by any appropriate fastening means. The apices of the V-shaped hangers protrude sufficiently above the edges of the belt to permit the 105 straps 7 to be conveniently secured thereto.

The trousers may be attached to the belt by a plurality of clips 16, see Figs. 1 and 2. Each such clip comprises a rectangular member or loop 17, preferably of wire, provided 110 at its upper end with a cross plate 18, the edges 19 of which (Fig. 3) are turned under

and about the loop 17, and are recessed at their inner edges at 20, to receive and confine the hinge ears 21 of the tongue 22. The top of the loop 17 has hinged to it a locking member 23 comprising an outwardly depending portion 24 (Fig. 4) holding a clamping button 27, and inwardly depending leg members 25. These legs overlie two notches 30—31 (Fig. 5) upon the tongue 22. 5 When the tongue is in raised position, as indicated by dotted lines, Fig. 4, the locking member 23 is in its dotted or unlocked position. By pressing down upon the tongue 22 the legs 25—25 of the locking member are 10 raised or turned outwardly from the plate 18 to close the button 27 upon and to closely grip the interposed band of the trousers, pressing the latter into a coöperating recess 32 in the said plate 18 which strengthens the 15 grip.

10 When the tongue is in raised position, as indicated by dotted lines, Fig. 4, the locking member 23 is in its dotted or unlocked position. By pressing down upon the tongue 22 the legs 25—25 of the locking member are 15 raised or turned outwardly from the plate 18 to close the button 27 upon and to closely grip the interposed band of the trousers, pressing the latter into a coöperating recess 32 in the said plate 18 which strengthens the 20 grip.

To use my garment supporter, the belt is first positioned inside the waist band of the trousers and the locking members 23 slipped over the upper edge of said waist band. The 25 tongues 22 are then depressed to firmly grip the trousers band. The straps 1—1 having been slipped over the shoulders, the strap 7 is clasped to the connector 6 by means of the 30 clasp 8, and the belt is adjusted to the waist measurement and the ends secured by the clasp 15 and ring 14.

When desired, the belt may be readily unclasped at 8 from the shoulder straps. While the belt is sufficiently rigid, vertically, 35 to hold the trousers suspended in position about the body, the suspension is really from two points only, directly beneath the shoulders, thus relieving the back and chest from any pressure of the shoulder straps, whether 40 the body is in an upright or stooping pos-

ture, and bringing the weight of the trousers at all times directly upon the tops of the shoulders, thus permitting much freer movement of the body when bending over than would otherwise be the case.

Depending from the side straps 7 are short straps 11, provided with clasps 12 at their lower ends, and adapted to be fastened to the band of the underdrawers to support the same in a manner similar to the trousers.

50

Claims—

1. A garment supporter comprising in combination shoulder straps having front terminal connecting members, a metallic connector for the opposite ends of each strap 55 having divergent ends, a clasp attached to the intermediate portion of each connector, and a metallic hanger attached by its intermediate portion to each connector and having downwardly divergent ends for connection to a garment belt or band.

2. A trousers supporter comprising in combination shoulder straps having separated ends, a wire connector secured to the opposite ends of each strap and positively spacing said ends apart, a clasp attached to the intermediate portion of each connector, a substantially inverted V shaped wire hanger attached by its intermediate portion to each clasp and having hooked lower ends, and a 60 trousers supporting belt sustained by said hooked ends and having means for connecting it to the trousers.
